UNITED STATES PATENT OFFICE.

WILLIAM M. EISEN, OF NEW YORK, N. Y.

SHOULDER-BRACE.

No. 883,101.

Specification of Letters Patent. Patented March 24, 1908.

Application filed December 16, 1907. Serial No. 406,704.

To all whom it may concern:

Be it known that I, WILLIAM M. EISEN, a citizen of the United States of America, residing at New York city, New York, have invented certain new and useful Improvements in Shoulder-Braces, of which the following is a specification.

The present invention relates to shoulder braces of the class in which two independent back stays are employed which are held together by suitable lacing.

In shoulder braces as heretofore constructed, it was customary to secure the back stays together and to employ a single continuous lacing cord for tightening the brace about the body. This form of brace has been found unsatisfactory because the attachments of the stays resulted in the production of a brace which was not sufficiently yielding and did not readily adapt itself to the irregularities of the body and the use of a single continuous lacing cord generally had the effect of drawing the stays crooked when the cord was pulled tightly as it was required to be in order to make the brace fit.

It is the purpose of my construction to overcome these several disadvantages in existing braces and this result is accomplished by providing two entirely independent back stays and connecting them by a series of independent lacing cords secured in such a manner that the brace while readily adapting itself to the contour of the wearer's body, may at the same time be so tightened as to act truly in the sense of a brace without causing discomfort to the wearer.

An embodiment of the invention is illustrated in the accompanying drawing, wherein

Figure 1 is a perspective view of a brace disclosing my invention; Fig. 2 is a fragmentary view of a brace and is designed particularly to illustrate the manner in which the lacing cords are secured to the back stays; and Fig. 3 is a sectional view taken on a plane through a pair of adjacent eyelets.

Referring to the drawings, 1 1 represent the back stays which are made of any suitable material and are provided with appropriate shoulder straps 2 2 each of which is connected to one of the back stays by an elastic member 3, the free end of the shoulder strap being adapted to be adjustably held to the back stay by engagement with a buckle 4 4 each shoulder strap at or about its intermediate portion 5 being padded so as to rest easily in the region of the arm pit of the

wearer. The adjacent longitudinal edges of the back stays 1 are provided with a series of regularly spaced eyelets 6, through which a series of lacing cords 7 is passed as described hereinafter.

In the preferred form of construction I provide as many lacing cords 7 as there are eyelets in both back stays. The form illustrated in the drawing shows 18 such independent lacing cords, one end 7' of each lacing cord being secured adjacent an eyelet 6 between the material of which the back stay 1 is formed and the outer end of such lacing cord being held in one of the waist bands 8 of which two are provided, one of the waist bands preferably having a buckle 9 to receive the free end of the opposite waist band. The lacing cords are so arranged that each pair of cords secured near opposite adjacent eyelets 75 run parallel from eyelet to eyelet and are then crossed on the outside of the back stay and have their other ends run to the waist bands 8 and secured therein as will be clear from Figs. 1 and 2.

A very material advantage resulting from the present construction is that a shoulder brace made according to the present invention is suitable for persons of various sizes, inasmuch as the two stays being unsecured or rather not attached to each other, they may be let out to a suitable extent and still be thoroughly tightened.

A further advantage arises from the peculiar method of lacing, it being found that when pulling upon the waist bands to tighten the lacing, the back stays will be drawn towards each other uniformly and evenly and when the waist bands are secured, the brace will effectively perform the function for which it is designed.

Another advantage in using separate lacing cords is found in the fact, that if any one cord should break it may be renewed without the necessity of renewing the other cords, whereas if but a single lacing cord were employed, it is obvious when the cord breaks in a certain place, it must be renewed as a whole, thus not only incurring the cost of the new cord but also incurring the cost of time and labor in putting the lacing cord into place.

Having thus described my invention, what I claim as new and desire to secure by Letters Patent is:

1. In a device of the character described, 110 the combination with a pair of back stays provided with eyelets along their adjacent

edges, of means for adjustably holding said back stays together, said means comprising as many lacing cords as there are eyelets, each lacing cord having one of its ends secured to the back stay adjacent an eyelet and running parallel for a portion of its length with the lacing cord secured in the back stay near the eyelet opposite to said first mentioned eyelet.

2. In a shoulder brace of the character described, the combination with a pair of back stays provided with eyelets along their edges, shoulder straps secured to said back stays by elastic members, waist bands, and means for adjustably holding said back stays together, said means comprising a series of independ-

ent lacing cords, there being as many lacing cords as there are eyelets and each lacing cord having one end secured in proximity to an eyelet and passing parallel for a portion of its length to the lacing cord secured near the eyelet opposite to the first mentioned eyelet, and said lacing cords being then crossed outside the back stays and having their opposite free ends secured to said waist bands.

In testimony whereof I have affixed my signature in presence of two witnesses.

WILLIAM M. EISEN.
